UNITED STATES PATENT OFFICE.

OSCAR OLSON, OF BROOKLYN, NEW YORK.

SHOE-TREE-FORMING MACHINE.

Application filed August 3, 1922. Serial No. 579,518.

To all whom it may concern:

Be it known that I, OSCAR OLSON, a citizen of the United States, and resident of the city of New York, borough of Brooklyn, in the county of Kings and State of New York, have invented a new and Improved Shoe-Tree-Forming Machine, of which the following is a full, clear, and exact description.

My invention relates to a shoe tree forming machine, and aims to provide a device of this character for the making of parts of shoe trees, although I wish it understood that the same may be employed for other purposes.

15 A primary object of the present invention is to provide a machine which will include a mechanism capable of handling any desirable number of members to be formed (such as shoe trees) this handling or manipulating being accomplished in an extremely efficient and positive manner, the mechanism further embracing structure by means of which a single operator is enabled to control all parts of the machine, and to actuate the mechanism thereof to properly manipulate the articles being formed.

A second object of the invention is that of constructing a device of the character stated which may simultaneously form any desirable number of objects, such as parts of shoe trees, in the shortest interval of time, and by means of which wastage will be reduced to a minimum.

With these and numerous other objects in mind the present invention consists in the provision of a machine which in turn supports members such as blocks of wood, whereby upon an operator following the outline or guide provided by the model, the members will be correspondingly manipulated together with mechanism serving to operate upon these members to properly shape the same during this movement.

Reference is had to the attached sheets of drawings as illustrating one practical embodiment of my invention, and it will be seen that—

Figure 1 is a plan view of a duplicating machine embodying my improved construction.

Figure 2 is a front view thereof, and showing certain of the exterior parts broken

away to disclose the underlying construction.

Figure 3 is a sectional side elevation of 55 the said machine taken along the line 3—3 and in the direction of the arrows indicated in Figure 2.

Figure 4 is a fragmentary side view showing the co-operation of certain parts. 60

Figure 5 is a further fragmentary side elevation partly in section, and showing in detail, the mechanism employed to produce the result desired.

Figure 6 is a sectional side view of one 65 of the member retaining elements.

Figure 7 is a transverse sectional view taken along the line 7—7 and in the direction of the arrows indicated in Figure 6.

Figure 8 is a front elevation of the trans- 70 verse saw operating mechanism.

Figure 9 is an enlarged sectional front view of a detail of the said saw.

Figure 10 is a transverse sectional view 75 of the same taken along the line 10—10 and in the direction of the arrows indicated in Figure 9.

Figure 11 is an enlarged fragmentary plan view of a certain detail of this mechanism. 80

Figure 12 is a fragmentary plan view of those parts of the mechanism which are essential to the splitting of the articles, and showing the same in operation, and

Figure 13 is a side elevation of one of the 85 finished articles which may be constructed by means of my machine.

Referring primarily to Figures 1, 2 and 3, it will be seen that in the embodiment illustrated, I show my machine as embracing a 90 main frame 15, supporting a power shaft 16 in suitable bearings 17. The frame also carries, by means of brackets 18, a counter shaft 19, the ends of which I prefer to support in brackets 20, which latter are mounted for slidable movement within slots 21 formed in the frame 15, and extending longitudinally thereof, it being noted however, that movement of the brackets 20 is normally prevented by means of bolts 22 95 which engage the frame for this purpose. Thus should an operator find it necessary to remove certain of the devices hereinafter described, which are associated with the

shaft 19, it will be apparent that the brackets 20 may be moved bodily to effect a detachment of these devices.

The driving or power shaft 16 serves to 5 rotate the counter-shaft 19 by any suitable form of connection such as bolts 23, which extend between pulleys associated with these shafts, and the counter-shaft 19 also has a battery of saws and cutting wheels 10 secured to its body which are preferably arranged in groups, each including a cutting wheel 24, and a saw 25. I wish it understood that any desirable number of these units may be affixed to the shaft 19, and this 15 shaft further carries a suitable guide member 26 which is arranged adjacent to an indicating member such as a pointer 27 carried by the frame 15.

A secondary frame identified by the reference numeral 28 is positioned adjacent to the shaft 19 and is supported at this point by means of arms 29 rockingly carried by the shaft 30, and each supporting a counter-balance 31 at a point beyond this shaft, the 25 upper ends of these arms providing bearing members 32 which support trunnions 33 affixed to the frame 28. Thus it will be obvious that the entire frame 28 may be swung with respect to the frame 15 by virtue of the support provided by the arms 29, and it will be seen that this frame may in turn be swung with respect to the arms 29 by virtue of the connection established by the bearings 32, and the trunnions 33. 30 Thus the members carried by the frame 28 may be swung towards and away from the shaft 19 and also upwardly and downwardly with respect thereto for a purpose hereinafter brought out.

40 Also as in Figures 1 to 3 it will be seen that a plurality of units are supported by the frame 28 which correspond in number to the number of groups of cutting wheels 24, and saws 25 provided, and the detailed 45 construction of each of these units is illustrated in Figures 6 and 7 in which it will be seen that the same comprises a drum 34 rotatably mounted within a sleeve 35, which is in turn supported by the frame 28. The 50 drum 34 is provided with a head 36, and this head together with the head 37 associated with the opposite end of the drum, serves to support a shaft 38 mounting cams 39. Each of the heads is formed with an 55 opening which may be quadrangular, as has been shown, so that a block of wood 40, or other suitable member may be supported thereby, and by providing a handle 41 in association with the shaft 38, the latter may be turned subsequent to the insertion of the member 40 to this position, so that the cams 39 carried thereby will engage the member to prevent any movement of the same with respect to the drum.

60 As aforesigned, any desirable number of

units of this nature are carried by the frame 28, and with a view of synchronizing the movements of said units, it will be noted that each of the heads 36 provides a radial series of teeth 42, and a serrated bar 43 has 70 its teeth engaging the teeth of all of these heads. Now by associating a hand wheel 44 or other suitable element with one of these units, and more particularly the head thereof, by any suitable means such as bolts 75 45, it will be understood that an operator may revolve the drum, and the member carried thereby, by simply grasping the hand wheel and rotating the same, which rotation will be transmitted, by virtue of the engagement of the bar 43 with the teeth 42, to the heads of all of the units, thus revolving the latter in synchronism to the 80 one actuated by the operator.

Thus by associating a model in the nature 85 of a perfect member 46 with one of the units aforescribed, it will be obvious that this model may be brought to a position adjacent the guide 26, it being of course understood, that, as in the embodiment illustrated, the model receiving unit is positioned adjacent to this guide. Upon the shaft 19 now being rotated, an operator may move the entire frame 28 in the manner hereinbefore set forth, to bring the 90 members 40 and model 46 into engagement with the cutting wheels 24 and the guide 26 to thus shape the members 40 to conform to the model. Also in addition to the contact aforesaid, it will be understood 95 that the model 46 and the members are rotated by the use of the hand wheel 44, and thus the entire outer ends of the members 40 are cut to conform to the shape desired, this result being further accomplished by 100 the use of the swinging action afforded by the trunnions 33 and the bearings 32. After the shaping operation has been 105 accomplished, an operator is at liberty to pull the frame 28 rearwardly so as to move the model 46 out of contact with the guide 26, and to correspondingly move the members 40 out of contact with the cutting wheels 24, it being understood that all of these operations are greatly facilitated by virtue of 110 the counter-balance established by the 115 weights 31.

During the operation aforescribed, the parts will co-operate as in Figure 4, and this co-operation will be continued until 120 the ends of the each of the members 40 assume the shape shown in Figure 12. In other words the ends of the members or wooden blocks 40 will be shaped to present two tree portions arranged with their lower 125 faces abutting, and being integral with each other. Now with a view of separating these tree portions it will be noted that I provide the saws 25, and the shaft 30 may be moved from the full line position shown in Figure 130

2 to that indicated in dotted lines by any suitable means such as a shaft bar 47 having a fork 48 co-operating with the collar 49 secured to the said shaft. Incident to the 5 fact that the shaft supports the secondary frame 28 by means of the arm 29 it will be obvious that this shifting will result in a shifting of the frame. Thus the model 46 will be brought into alignment with the 10 pointer 27, and an operator may now move the entire frame 28 towards the shaft 19. Incident to the fact that the parts are so disposed that when the pointer 27 is in line with the model, the central portion of the 15 members 40 will be in line with the saws 25, it will be obvious that this movement of the frame will cause the saw to engage the outer shaped end of the members 40 to cut the same longitudinally as in Figure 12, 20 thus accomplishing the second operation of the machine.

Now with a view of providing a mechanism which will serve to transversely cut the members 40, it will be seen that the 25 frame 28 carries an extension 50 which in turn carries arms 51 providing a dovetailed track, as best shown in Figure 3. Slidably mounted in this track is a bar 52 which supports a plurality of guards corresponding in number to the number of units employed, and each of these guards preferably comprises, as in Figures 8, 9, 10, and 11 a frame 53 within which a saw 54 is disposed by means of a support 55, which 30 latter in the embodiment illustrated mounts a roller 56 adjacent its lower face.

These saws may be reciprocated in any desirable manner, but in the embodiment illustrated it will be noted that I have 40 shown an arm 57 connected to the bar 52, and this arm is moved by a pitman 58 connected to a suitable source of power supply, such as a motor 59, carried by the extension 50. Thus it will 45 be obvious that upon the motor 59 being actuated the arm 57 of the bar 52 will be reciprocated within the track provided in the arms 51, and incident to the fact that this bar rigidly supports the frame 53 carrying the saws 54, it will be obvious that 50 the latter will be moved backward and forward along the track. To bring these saws to a position at which they will perform the cutting operation desired, I may utilize 55 a lever 60, which is pivotally carried by the extension 50 and the inner end of this lever is attached to a bracket 61 supporting tables 62 adjacent its ends. These tables underlie the split portion of the bar 52, and thus 60 upon the same being projected upwardly by an actuation of the lever 60, it will be obvious that the saws 54 will also be moved upwardly within their frames 53, incident to the engagement of the roller 56 with the 65 tables 62 provided for this purpose.

Thus a third operation of the device consists in the operation of the mechanism in the manner aforescribed which will cause the members 40 to be cut transversely so that finally the divided outer end of each of 70 the members is cut transversely to provide two tree portions, one of which has been shown in Figure 13 and identified by the reference numeral 63.

Summing up the operation of this device 75 it will be understood that the same, although not necessarily limited to this particular use, is essentially a machine primarily intended for the manufacture of tree portions and similar articles, the mechanism provided enabling a workman to simultaneously operate upon a number of tree portions. Thus any desired number of units are provided, and each of these units supports a block, and one of the same takes the 80 form of a model positioned adjacent to suitable guide members such as has been illustrated. The machine is now set in operation, and these members are engaged by the cutting wheels 24 to shape the ends of 85 the same, it being of course understood that previous to this actuation of the parts, the members are clamped into position by means of the locking mechanism shown. Incident to the great latitude of movement 90 allowed these members, due to their mounting, the same will be quickly and accurately shaped to correspond to the model, and the second operation of the mechanism, i. e., that of bringing the shaped ends of the 95 members into alignment with the saws 25, and the subsequent engagement of these parts, will cause the latter to penetrate the ends of the members to cut the same longitudinally, as in Figure 12. The tree portions are now completed, and to sever these 100 articles from the body of the members, the saws 54 are caused to operate subsequent to which they are projected to a position at which they will engage the underside of the 105 members 40 adjacent the outer ends of the same, thus severing those portions of the members beyond the point at which they engage with the same, or in other words, adjacent the base of the tree portions. 110

Thus all of the objects of this invention have been accomplished and it will be understood that numerous modifications of structure might readily be resorted to without in the least departing from the scope of my 115 claims, which are—

1. In a machine for making shoe tree parts, a frame, a second frame movably connected to said first named frame, a shaft rotatably carried by said first named frame, groups of cutting wheels and saws carried by said shaft, article retaining units carried by said second frame and corresponding in number to the number of groups aforementioned, cutting devices carried by said 125 130

- second frame adjacent to said units, and means for operating and projecting said last named cutting devices, whereby to bring the same into engagement and to transversely sever the articles carried by said units.
2. In a machine for making shoe tree parts, a frame, a second frame movably connected to said first named frame, a shaft rotatably carried by said first named frame, groups of cutting wheels and saws carried by said shaft, article retaining units carried by said second frame and corresponding in number to the number of groups aforementioned, cutting devices carried by said second frame adjacent to said units, means for reciprocating said cutting devices, and means for projecting the same to a position at which they will transversely sever the articles carried by said units.
3. In a machine for making shoe tree parts, guiding and cutting mechanisms, model and article retaining units movable into cooperative relation with said guiding and certain of said cutting mechanisms, respectively, to cut the articles carried by said article retaining units in conformity with the configuration of the model supported by said model retaining unit, means for moving said article retaining units laterally with respect to said cutting mechanisms and toward certain others of the latter to cut said articles longitudinally, and a cutting device movable toward and transversely of said articles to further cut the same.
4. In a machine for making shoe tree parts, guiding and cutting mechanisms, model and article retaining units movable into cooperative relation with said guiding and certain of said cutting mechanisms, respectively, to cut the articles carried by said articles retaining units in conformity with the configuration of the model supported by said model retaining unit, means for moving said article retaining units laterally with respect to said cutting mechanisms and toward certain others of the latter to cut said articles longitudinally, a cutting device movable toward and transversely of said articles to further cut the same, and means for rotating said model and article retaining units during the first mentioned cutting operation.
5. In a machine for making shoe tree parts, guiding and cutting mechanisms, model and article retaining units movable into cooperative relation with said guiding and certain of said cutting mechanisms, respectively, to cut the articles carried by said article retaining units in conformity with the configuration of the model supported by said model retaining unit, means for moving said article retaining units laterally with respect to said cutting mechanisms and toward certain others of the latter to cut said articles longitudinally, a cutting device mov-

able into engagement with said articles, and means for reciprocating said cutting device to cut said articles transversely.

6. In a machine for making shoe tree parts, guiding and cutting mechanisms, model and article retaining units movable into cooperative relation with said guiding and certain of said cutting mechanisms, respectively, to cut the articles carried by said article retaining units in conformity with the configuration of the model supported by the model retaining unit, means for rotating said model and article retaining units during said cutting operation, means for moving said article retaining units laterally with respect to said cutting mechanisms and toward certain others of the latter to cut said articles longitudinally, a cutting device movable into engagement with said articles, and means for reciprocating said cutting device to cut said articles transversely.

7. In a machine for making shoe tree parts, a main frame, article cutting mechanisms carried by said frame, a second frame pivotally connected to said main frame and movable toward and away from said cutting mechanisms, article retaining units carried by said second frame and movable therewith into cooperative relation with certain of said cutting mechanisms, means for further moving said second frame longitudinally of its pivot to adjust said article retaining units into cooperative relation with others of said cutting mechanisms, and a cutting device carried by said second frame and having an initial movement with respect thereto to engage the same with the articles carried by said article retaining units and subsequent movements relative to said second frame to cut said articles.

8. In a machine for making shoe tree parts, a main frame, article cutting mechanisms carried by said frame, a second frame supported by the first named frame and having movements toward said cutting mechanisms and laterally with respect thereto, article retaining units carried by said second frame and cooperating with certain of said cutting mechanisms when said second frame is moved toward said mechanisms, said retaining units cooperating with others of said cutting mechanisms when said second frame is moved laterally and toward said mechanisms, and a cutting device carried by said second frame and having an initial movement with respect thereto to engage the same with the articles carried by said article retaining units and subsequent movements relative to said second frame to cut said articles.

9. In a machine for making shoe tree parts, a main frame, article cutting mechanisms carried by said frame, a second frame pivotally connected to said main frame and

movable toward and away from said cutting mechanisms, article retaining units carried by said second frame and movable therewith into cooperative relation with certain of said cutting mechanisms, means for further moving said second frame longitudinally of its pivot to adjust said article retaining units into cooperative relation with others of said cutting mechanisms, and

a cutting device carried by said second frame and having an initial movement with respect thereto to engage the same with the articles carried by said article retaining units and subsequent reciprocating movements relative to said second frame to cut said articles.

OSCAR OLSON.
